UNITED STATES PATENT OFFICE.

MARGARET B. PHILIPS, OF PORT ALLEGANY, PENNSYLVANIA.

DESIGN FOR A DOLL.

49,779.

Specification for Design.

Patented Oct. 17, 1916.

Application filed August 21, 1916. Serial No. 116,208. Term of patent 7 years.

To all whom it may concern:

Be it known that I, MARGARET B. PHILIPS, a citizen of the United States, residing at Port Allegany, in the county of McKean and State of Pennsylvania, have invented a new, original, and ornamental Design for a Doll, of which the following is a specification, reference being had to the accompanying drawing, forming part thereof.

The figure is a face view of a doll embodying my design.

I claim:

The ornamental design for a doll, as shown.

MARGARET B. PHILIPS.

Witnesses:

M. N. ALLEN,
B. M. PHILIPS.
